UNITED STATES PATENT OFFICE.

JOHN THOMAS, OF CEDAR RAPIDS, IOWA.

HARNESS-PAD PLATE.

SPECIFICATION forming part of Letters Patent No. 244,338, dated July 12, 1881.

Application filed June 6, 1881. (No model.)

To all whom it may concern:

Be it known that I, JOHN THOMAS, of Cedar Rapids, in the county of Linn and State of Iowa, have invented new Improvements in Harness-Pad Plates; and I do hereby declare the following, when taken in connection with the accompanying drawings and the letters of reference marked thereon, to be a full, clear, and exact description of the same, and which said drawings constitute part of this specification, and represent, in—

Figure 1, a perspective view; Fig. 2, a vertical central section, enlarged.

This invention relates to an improvement in harness-pad plates, the object being to avoid the leather covering of the jockey usually employed to securely attach the skirt, and avoid the use of extra pad-screws; and the invention consists in the construction as hereinafter described, and particularly recited in the claims.

A represents the pad-plate, constructed with a flange, *a*, at each side, the plate extending down toward each end, turned up, and terminating, as at B, in the usual form of the jockey.

Through the plate are the usual openings, *b*, for the water-hook, and *d d* for the terret, and the usual back-strap loop, *C*, on the rear edge, at the center.

The side flanges, *a*, are extended downward below the ends of the jockey, and a loop, *D*, extends across from the flange at one side to the flange on the opposite side, so as to leave an opening, *e*, below the end of the jockey. At this opening, and at the lower edge of the flanges, *a*, is a transverse bar, *f*, and on the under side of the jockey is a stationary stud or hook, *h*. This completes the construction.

The skirt is attached to the bar *f* below the loop *D*, the said loop serving to hold the skirt 40 solid at that point where it is first attached to the jockey.

The covered jockey admits the skirt beneath the plate, thereby dispensing with the usual leather cover, and permits the finishing of the 45 upper surface smoothly.

The stud or safety-hook *h* takes the place of the extra pad-screw to hold the skirt in place, and because of being a permanent part of the plate cannot become loosened, as the pad- 50 screws frequently do.

I claim—

1. The herein-described harness-pad plate, consisting of the plate *A*, terminating at its ends in the covered jockey *B*, constructed with 55 flanges *a* upon its edges, the said flanges extending beyond the jockey, their ends connected by a loop, *D*, so as to leave a space between said loop and the jockey, and with a transverse bar, *f*, between the flanges at said 60 recess, substantially as described.

2. The herein-described harness-pad plate, consisting of the plate *A*, terminating at its ends in the covered jockey *B*, constructed with flanges *a* upon its edges, the said flanges extending beyond the jockey, their ends connected by a loop, *D*, so as to leave a space between said loop and the jockey, and with a transverse bar, *f*, between the flanges at said 65 recess, and a stud or safety-hook, *h*, upon the 70 under side of the jockey, substantially as described.

JOHN THOMAS.
